UNITED STATES PATENT OFFICE.

LEON WYGODSKY, OF BALTIMORE, MARYLAND.

SPRAYER.

1,250,067.

Specification of Letters Patent. Patented Dec. 11, 1917.

Application filed January 15, 1917. Serial No. 142,345.

To all whom it may concern:

Be it known that I, LEON WYGODSKY, a citizen of the United States of America, and a resident of Baltimore, Maryland, have invented certain new and useful Improvements in Sprayers, of which the following is a specification.

My invention relates to improvements in sprayers, for example that type thereof employed for the injection of fuel into the cylinders of internal combustion engines. The sprayer herein illustrated and described, embodies the invention of the sprayer illustrated in the application of Albert W. Gieske and myself, Serial No. 86,183, filed March 23, 1916, in which application the said sprayer is stated to be of my invention. But the sprayer herein described also embodies improvements upon the sprayer illustrated in the said Gieske-Wygodsky application. As in the sprayer of that application, the spraying of the oil is effected in large degree by the pressure under which that oil is supplied to the sprayer; but in addition, in the improved sprayer herein illustrated and described, I provide a separate inlet for air or other suitable gas under high pressure, which air or other gas is so employed in the sprayer as to materially improve the spraying of the oil, and in particular to spray the oil more finely and widely.

My invention consists in the novel construction of the sprayer; in novel means whereby the action of air or other gas under high pressure is added to the action of the pressure of the oil, for the wide and uniform spraying of the oil, and in other features as hereinafter described and pointed out in the appended claims.

The object of my invention is to improve sprayers, for example sprayers intended for the spraying of heavy oils into the cylinders of internal combustion engines, and to make the sprayer relatively simple in construction, and extremely durable and reliable; also, to regulate automatically the rate of flow of air with variation of rate of supply of oil, and thereby economize in the use of air under pressure.

I will now proceed to describe my invention with reference to the accompanying drawings, and will then point out the novel features in claims. In said drawings:

Figure 1 shows a longitudinal section of the sprayer;

Fig. 2 shows, on a larger scale, a longitudi-

dinal section of the lower portion of the sprayer;

Fig. 3 shows a transverse section of the lower portion of the sprayer on the line 3—3 of Fig. 2;

Fig. 4 shows an end view of the sprayer cone, and in particular shows the grooves in that cone.

Fig. 5 shows a transverse section on the line 5—5 of Fig. 2.

My improved sprayer consists of an outer tube, 1, provided with suitable means, as for example the enlarged screw threaded portion 2, for its attachment to the cylinder or cylinder head of an internal combustion engine. In Fig. 1, 3 designates a portion of a cylinder or cylinder head of an engine, 4 designates a sleeve threaded into a suitable port of that cylinder head, and flanged at its upper end, and 5 designates a coupling nut whereby the tube 1 is held in place within the sleeve 4.

6 designates a tube forming in effect an extension of tube 1, and screw-connected at its lower end to said tube 1.

7 designates a plunger, within tubes 1—6, and itself preferably of two part construction, in that its upper portion, 8, is connected to the main portion, 7, by means of a sleeve 9 pinned at 10 to the portion 8 and fitting over a squared portion 11 of the main portion 7 of the plunger, the portion of the sleeve 9 which fits over the squared portion 11 being correspondingly squared so that rotation of the portion 8 also rotates the portion 7. This plunger 7 is pressed downward by a spring 12 acting upon a small piston 13 fitting over a reduced portion of the plunger-section 8 and working in the tube 6 as a guide. At its upper end, this spring 12 seats against a bushing 14 screwed into the upper end of the tube 6. The pressure exerted by the spring may be regulated by turning this bushing 14.

The main portion 7 of the plunger screws over the rear end of a bushing 15, which bushing 15 has a reduced portion 16 at its lower end and works in an internal recess of another bushing 17 screw threaded into a recess in the lower end of tube 1. This bushing 17 is itself recessed at its lower end to receive the spray cone 18, which cone, at its lower end, is provided with the two series of spiral grooves 19 and 20, herein-after referred to.

Bushings 16 and 17, and the cone 18, are

provided with axial bores, in line with one another, and within which bores there is a headed plunger 21, pressed downward by a spring 22 located in a recess in the end of the plunger 7; such plunger 21 being provided, at its lower end, with a needle termination 23, adapted to coact with the spray orifice 24 of a spray tip 25; with the inner coned surface 26 of which spray tip the end 10 surface of the spray cone 18 coacts.

Tube 1 has two supply connections 27 and 28, connected with ducts 29 and 30 respectively, of which 29 leads to the space between bushings 15 and 17, while 30 leads to the 15 space 31 between the end of tube 1 and spray tip 25. Connection 27 may be understood to be for oil or other fluid, and connection 28 for air or other gas. The longer series of grooves 20 in the end of cone 18 (see Fig. 4) communicates with this space 31 and serves to conduct air between the spray cone 18 and the spray tip 25, to the spray orifice 24. As will be apparent from Figs. 2, 3 and 5, the portion 16 of bushing 15 is shaped to 20 provide passages 32 leading from space 33 (with which duct 29 connects) to a space 34 within bushing 17; and since the lower portion 35 of plunger 20 is of triangular cross-section, as indicated particularly in Fig. 3, 25 spaces are provided for the downward flow, along that plunger, of fluid from duct 29 into space 36, with which space the grooves 19 of the spray cone 18 communicate.

The construction is such that oil or other 30 fluid to be sprayed, admitted at connection 27, and thence flowing, through duct 29 and spaces 33, 32 and 34, will reach grooves 19. This fluid being supplied under pressure (and, preferably, being supplied intermittently by the successive strokes of a reciprocating pump) forces backward the plunger 7 against the pressure of the spring 21 and, in so doing, raises the needle valve 23, so that such fluid passes from space 36 into the 40 grooves 19 and thence out through spray orifice 24. Owing to the curvilinear form of the grooves 19, a rotation is imparted to the fluid so issuing through spray orifice 24. Air or other gas supplied by duct 30 to 45 space 31 and thence to the grooves 20, issues with the fluid from duct 29, and owing to the curvilinear form of the grooves 20, a rotation is imparted to this gas stream also. The air or other gas, and oil or other fluid 50 mix very thoroughly, and the gas in rushing out and expanding serves to facilitate very greatly the wide spraying of the oil.

Since, as will be apparent from Fig. 5, the bushing 15, forming the lower termination of the plunger 7, has a "bit" or "screw-driver" engagement with the bushing 17, rotation of the plunger 7—8 will adjust the position of the spray cone 18 with reference to spray tip 25. Such rotation may be effected conveniently by means of the knurled

head 37 at the upper end of the plunger member 8. A spring dog 38 secured to the outer casing member 6, engages one or another of the serrations of the knurled head, tending to hold that knurled head in any 70 position to which it may be adjusted.

Bushing 15 is to be regarded as in effect, a part of plunger 7; and bushing 17 is to be regarded as, in effect, a part of spray-cone 18.

Any oil which may leak past the plunger 75 will collect in the space between tube 6 and plunger member 8, and if any such leakage passes piston 13, it will escape through leakage port 39, to which port a suitable leakage pipe may be connected.

It will be understood that in the operation of this sprayer, and with the liquid to be sprayed supplied by the intermittent action of a reciprocating pump, the plunger 7, and bushing 15, move back and forth slightly 85 under the intermittent pressure of the liquid to be sprayed, opposed by the action of the spring 12; but the bushing 17 and spray cone 18, as well as the spray tip 25 remain stationary (except as, by operation of the 90 knurled head 37, the bushing 17 and spray cone 18 may be rotated and therefore advanced or retracted, as the case may be, for adjustment of distance between the coacting surfaces of members 18 and 25). The small 95 plunger 21, having the needle point 23, is flexibly connected to plunger 7 by means of the spring 22, which serves the purpose of eliminating, as to said small plunger, the pressure of the much heavier spring 12 100 which acts upon the main plunger 7—8. In the operation of the sprayer, owing to the pulsating supply of the fluid to be sprayed, as previously explained, both the main plunger 7—8 and the small plunger 21, move 105 back and forth, due to the pulsating action of the fluid sprayed upon them; the small plunger 21 moving back to open the port 24 so permitting exit of the fluid sprayed, and then closing that port 24 again as soon as the 110 pressure of the liquid upon it has ceased.

This sprayer is not restricted in any way to use with internal combustion engines, but may be used in reaction apparatus generally, for example, such apparatus as is 115 shown and described in the said Gieske-Wygodsky application Sr. No. 86,183, above referred to; also this sprayer may be used in various other connections. Either a liquid or a gas may be supplied at either or 120 both of the connections 27 and 28; that is to say, the sprayer may be used for the mingling not only of a gas with a liquid, but of a gas with another gas, or of a liquid with another liquid. In a word, the sprayer 125 is not limited to use with any particular substances or for any particular reactions; and while I have termed it a sprayer, still it may be used for general mixing purposes where mixing rather than spraying is the 130

object. It will be noted that the two substances to be mixed together are kept entirely separate in the device until the extreme point of exit is reached; and thereby 5 reactions within the device, of substances treated by that device, are avoided.

In particular, instead of supplying air under pressure at connection 28, oxygen or other gas under pressure may be admitted 10 there, either to facilitate combustion of a liquid or gaseous substance admitted into connection 27, or to facilitate other reactions; for example, the cracking of hydrocarbon oils.

15 The sprayer herein illustrated and described embodies the invention of my Patent No. 971,954, dated October 4, 1910, but comprises various improvements in mechanical construction, also means whereby the 20 sprayer is adapted for the mixing and conjoint spraying of a plurality of fluids.

What I claim is:

1. A sprayer such as described, comprising a hollow sprayer body, a perforate spray 25 tip at one end of said body and a coacting spray-producing member within said body and coacting with the inner surface of said spray tip, a plunger within said coacting spray-producing member having a needle 30 termination coacting with the orifice of said spray tip, and a further plunger within said sprayer body, and drivingly connected with said coacting spray-producing member to rotate the latter when itself rotated, said 35 coacting spray-producing member arranged to be advanced or retracted with reference to the spray tip, when so rotated, and means for conducting fluid to the space between said spray tip and said coacting spray-producing member.

2. A sprayer such as described, comprising a hollow sprayer body, a perforate spray 45 tip at one end of said body and a coacting spray-producing member within said body and coacting with the inner surface of said spray tip, a plunger within said coacting spray-producing member having a needle 50 termination coacting with the orifice of said spray tip, a further plunger within said sprayer body, and drivingly connected with said coacting spray-producing member to rotate the latter when itself rotated, said coacting spray-producing member arranged to be advanced or retracted with reference 55 to the spray tip, when so rotated, means for conducting fluid to the space between said spray tip and said coacting spray-producing member, and a spring within a recess in said further plunger pressing said first-mentioned plunger outward.

3. A sprayer such as described, comprising a hollow sprayer body, a perforate spray 65 tip at one end of said body and a coacting spray-producing member within said body and coacting with the inner surface of said

spray tip, a plunger within said coacting spray-producing member having a needle termination coacting with the orifice of said spray tip, and a further plunger within said sprayer body, and drivingly connected with 70 said coacting spray-producing member to rotate the latter when itself rotated, said coacting spray-producing member arranged to be advanced or retracted with reference to the spray tip, when so rotated, means for 75 conducting fluid to the space between said spray tip and said coacting spray-producing member, and elastic pressure means within said sprayer body and surrounding said further plunger and tending to press 80 the latter forward.

4. A sprayer such as described, comprising a hollow sprayer body, a perforate spray tip at one end of said body and a coacting spray-producing member within said body 85 and coacting with the inner surface of said spray tip, a plunger within said coacting spray-producing member having a needle termination coacting with the orifice of said spray tip, and a further plunger within said 90 sprayer body and at one end projecting from the rear of such body and at its other end drivingly connected with said coacting spray-producing member to rotate the latter when itself rotated, said coacting spray-producing member arranged to be advanced or retracted with reference to the spray tip, when so rotated, and means for conducting 95 fluid to the space between said spray tip and said coacting spray-producing member.

5. A sprayer such as described, comprising a hollow sprayer body, a perforate spray tip at one end of said body, and a coacting spray-producing member within said spray tip, and coacting with the inner surface of 105 said spray tip, a plunger within said sprayer body and projecting therefrom at one end and at its other end drivingly connected with said coacting spray-producing member to rotate the latter when itself rotated, said 110 coacting spray-producing member being arranged to be advanced or retracted, with reference to the spray tip, when so rotated, and means for conducting fluid to the space between said spray tip and said coacting 115 spray-producing member.

6. A sprayer such as described, comprising a hollow sprayer body, a perforate spray tip at one end of said body, and a coacting spray-producing member within said spray tip, and coacting with the inner surface of 120 said spray tip, a plunger within said sprayer body and projecting therefrom at one end and at its other end drivingly connected with said coacting spray-producing member 125 to rotate the latter when itself rotated, said coacting spray-producing member being arranged to be advanced or retracted, with reference to the spray tip, when so rotated, and means for conducting fluid to the space 130

between said spray tip and said coacting spray-producing member, and a piston within said sprayer body and mounted upon said plunger, said sprayer body having a leakage-escape port.

7. A sprayer such as described, comprising a hollow sprayer body, a perforate spray tip at one end of said body, and a coacting spray-producing member within said spray tip, and coacting with the inner surface of said spray tip, a plunger within said sprayer body and projecting therefrom at one end and at its other end drivingly connected with said coacting spray-producing member to 10 rotate the latter when itself rotated, said coacting spray-producing member being arranged to be advanced or retracted, with reference to the spray tip, when so rotated, and means for conducting fluid to the space 15 between said spray tip and said coacting spray-producing member, and a piston within said sprayer body and mounted upon said plunger, said sprayer body having a leakage-escape port beyond said piston, a bushing 20 surrounding the projecting portion of such plunger and fitting within the end of the sprayer body, to close the same, and a spring 25 for said plunger bearing against said bushing and against said piston.

8. A sprayer such as described comprising a hollow sprayer body, a perforate spray-tip at one end of said body and a coacting spray-producing member within said body and coacting with the inner surface of said spray 30 tip, and means for introducing two different fluids under pressure between the coacting surfaces of said spray tip and said spray-producing member, comprising ducts within said sprayer body leading to between the 35 said tip and said coacting spray-producing member.

9. A sprayer such as described comprising a hollow sprayer body, and a perforate spray tip at one end of said body, and a coacting 40 spray-producing member within said body, there being between the coacting surfaces of said tip and coacting member two series of 45 grooves leading to the orifice of said tip.

10. A sprayer such as described comprising a hollow sprayer body, and a perforate spray tip at one end of said body, and a coacting spray-producing member within said body, there being between the coacting surfaces of said tip and coacting member two 50 series of spiral grooves leading to the orifice of said tip.

11. A sprayer such as described comprising a hollow sprayer body, and a perforate spray tip at one end of said body, a coacting spray-producing member within said body, a 60 plunger within said coacting spray-producing member itself arranged to coact with the orifice of said spray tip, there being between the coacting surfaces of said tip and coacting spray-producing member two grooves leading to the orifice of said tip, one of said grooves leading from the bore of the coacting spray-producing member within which such plunger works, the other groove leading from another point, and means for conducting different fluids to be sprayed to the said spray-tip orifice, comprising ducts, one leading to the bore through which such plunger works, and thence to the groove 65 communicating with such bore, the other 70 leading to the point from which such other groove leads.

12. A sprayer such as described, comprising a hollow sprayer body, a perforate spray tip at one end of said body and a coacting spray-producing member within said body and coacting with the inner surface of said spray tip, a plunger within said coacting spray-producing member coacting at the one end with the said orifice of said spray tip, 80 said coacting member having a screw-thread connection with said sprayer body whereby rotation of such coacting member advances or retracts it with reference to said spray tip, a further plunger within said sprayer 85 body and drivingly connected with said coacting spray-producing member to rotate the latter when itself rotated, said plunger and coacting member formed to provide a channel for the flow of fluid to a space in said 90 coacting member, a duct for conducting fluid to such channel, a groove between the coacting surfaces of said spray-producing member and said spray tip leading from such space to the orifice of said tip, another 95 groove between the coacting surfaces of said spray tip and said spray-producing member leading from a further space to the orifice of the spray tip, and a further duct leading to such further space.

In testimony whereof I have signed this specification in the presence of two subscribing witnesses.

LEON WYGODSKY.
